DEVICE FOR DISTRIBUTING POWDERY SUBSTANCES

Filed Sept. 10, 1927

UNITED STATES PATENT OFFICE

LESTER B. PLATT, OF CALDWELL, NEW JERSEY

DEVICE FOR DISTRIBUTING POWDERY SUBSTANCES

Application filed September 10, 1927. Serial No. 218,609.

This invention relates to improvements in a device for distributing powdery substances and has for one of its objects the provision of an article of this kind which is efficient for the storage and distribution of condiments such as salt, pepper and the like and also other powdery substances, under all kinds of atmospheric conditions.

A further object of this invention is the provision of a device of this kind which is composed of few parts, may be readily and cheaply made of various materials, which is capable of adjustment so as to vary the quantity of the substance distributed and also permanently closed, and which is also susceptible to manufacture of materials of various colors whereby devices of attractive and ornamental appearance may be provided.

A further object is the provision of such an article by which the substance is distributed from the bottom of the article, a combined valve and distributing member forming the bottom of the device.

To the accomplishment of the foregoing and such other objects as may hereinafter appear, this invention consists in the construction, combination and arrangement of parts hereinafter described and then sought to be defined in the appended claims, reference being had to the accompanying drawings forming a part thereof and which show, merely for the purpose of illustrative disclosures, various embodiments of this invention, it being expressly understood, however, that various changes may be made in practice within the scope of the claims without digressing from my inventive idea.

In the drawings—

Figure 1 represents an elevation of a device constructed to embody my invention.

Figure 2 is a vertical central cross section through the same.

Figure 3 is a perspective view showing the various parts used in the construction of Figure 2, in unassembled relation.

Figure 4 is a detail perspective view of the upper part of the body of the device illustrating a modified form of neck.

Figure 5 is a detail perspective view of a

modified form of closing and distributing member.

Figure 6 is a detail perspective view of the upper portion of a body showing a modified form of neck and a split washer. 55

Figure 7 is a similar view of the upper portion of a body showing a further modification of a neck.

Referring now to the drawings and first to Figures 1, 2 and 3, the numeral 1 designates the body of the device as a whole. This may be formed in various shapes such as one of the conventional salt cellar shapes illustrated or in any other suitable and attractive form. It may be made of various materials such as glass, compositions of various kinds, which may be colored or ornamented in different ways, metal, etc. This body is hollowed out in the form of a casing having the opening 2 at its lower end, the lower edge of the casing being bevelled as at 3 to form a seat for the combined closing and distributing member. The other end of the body or casing 1 is formed with a neck 4 of solid material, which extends or projects upwardly therefrom. 70 This neck 4 is bored as at 5 to form a passage for the operating rod 6. This operating rod 6 is secured at its upper end to the operating button 7 which is hollow and has the extended sides 8 to fit over or overhang the edges of the neck portion 4. Spring member 9, which is preferably helical or conical, is positioned between the top of the neck 4 and the inside surface of the button 7 so as to force the button in an upward direction and thereby move 75 the rod upwardly. 80

The operating button 7 is bored in a plurality of places as at 10 to receive the adjusting members 11 which are in the form of screws having the studs or projections 12 on their lower ends. The upper surface of the neck 4 of the body is formed on an incline or a plurality of inclines to afford a plurality of cam surfaces 13 having abrupt shoulders 14 therebetween. The studs or projections 12 on the adjusting screws 11 engage these cam surfaces when the operating button is depressed so as to limit the downward movement of the operating rod 6. By turning the operating button these studs or projections 105

12 will be opposite a different portion of the cam surface and, therefore, the amount of downward movement of the operating button 7 may be varied by turning adjustment thereof.

5 The closing and distributing member 15 is of general disc shape having its outside edge bevelled as at 16 to provide the valve seating edge 17 which is adapted to engage the 10 bevelled surface 3 at the opening into the bottom of the body or casing. This closing and distributing member is formed or provided with the stud or projection 18 which is longitudinally bored as at 19 to receive the lower 15 end of the operating rod 6. A detachable connection is provided between the lower end of the operating rod 6 and the closing and distributing member 15 and this includes the coil spring 20, which is jammed or fits tightly 20 within the lower portion of the bore 19 and engages the lower end of the rod 6 when inserted therein, and a bayonet slot connection. This is provided by pins 21 on the lower part of the rod 6 and the bayonet slots 22 on the stud 25 or projection 18. When the parts are assembled so that the pins 21 enter the slots 22 and the closing and distributing member 15 and the operating rod 6 turn relative to each other, the pins 21 pass through the horizontal 30 portions of the bayonet slots 22 and engage the short upward portion of the slot 23, being held therein by the spring pressure. The closing and distributing member 15 may be provided with an aperture 24 to permit 35 the escape of any of the powdered substance which inadvertently enters the slot 22 and the bore 19 thereof.

40 The cam construction of the upper surface of the neck 4 of the body 1, of course, may be made in various ways. For instance, as shown in Figure 6, the cam surfaces may be in the form of cam ridges 25, which terminate short of each other to leave the slot or depression 26. In Figure 6 two of such cam 45 ridges are shown but more may be utilized (see Figure 7 where four of such cam ridges are shown with the depressions or slots 26 therebetween).

49 Another slight modification is illustrated in Figure 4 in which a groove or depression 27 is positioned adjacent the shoulders 14 and at the bottom of the cam surface. This slot is for the purpose of receiving the pin or projection 12 so as to permit a maximum depression of the operating cap or button, as will hereinafter be described. This last-mentioned form of construction is particularly useful in connection with large containers and for such device I may utilize a special form 55 of closing and distributing member (see Figure 5). The upper part 28 of this construction is the same as the previously described closing and distributing member 15. However, it is extended downwardly as at 29 and 60 has the spokes or ribs 30 radiating therefrom

to a base ring or rim 31, which is large enough to provide a secure foundation for supporting the larger container. The upper edges of these spokes or ribs are sharp as at 32.

5 In the construction shown in Figures 2 and 3 the operating button has a screw-threaded and detachable connection with the operating rod 6. It is possible that these parts may be permanently connected and in constructions in which this is done I provide (see Figures 6 and 7) grooves 33 extending laterally from the bore 5 through the neck 4 of the body. These grooves will permit the withdrawal of the pins 21 on the lower end of the operating rod. When this is used I also use a split washer 34 (see Figure 6) of flexible material to prevent leakage.

6 It is therefore seen that when the parts of this device are assembled the amount of movement between the closure and distributing member and the bottom edge of the body or casing 1 may be varied by turning either the closure or distributing member itself or the button. This varies the distance that the operating button may move when depressed as it is limited by the engagement of the studs or pins 12 with the cam surfaces 13. This affords a ready means for determining the amount of movement between the parts and the distance which the closure and distributing member may be moved away from the bottom edge of the body or casing, therefore determining the quantity of material to be distributed at any one time. This opening movement is accomplished by pressing on the button with the thumb or finger of the user against the normal pressure of the spring member 19, so that when the digital pressure is released, the parts will, because of the pressure of the spring, be forced to their normal closed position. Furthermore, when the device is at rest, the flat surface of the closure and distributing member may form the bottom or base of the device upon which the device as a whole rests, or may be extended as shown in Figure 5, with the resultant assistance in keeping the closure member tightly closed against the bottom edge of the body and casing.

115 The relative arrangement and size of the cam surfaces and the adjusting screws on the one hand and the bayonet and slot connection between the operating rod 6 and the closure and distributing member 15, preferably are so proportioned as to provide that the device 120 may be opened for filling and cleaning purposes at certain definite positions only, in what might be called "maximum position" or where the operating button may be depressed the greatest distance. This position will be 125 at the lowest point of the cams of Figures 2 and 3, or at the slot or depression 26 of Figures 6 and 7, or at the groove or slot 27 of Figure 4. Unless the pins 12 register with these slots or grooves or the lower portion of 130

the cam surfaces, insufficient movement is permitted between the closure and distributing member 15 and the lower edge of the body or casing. In other words, it is impossible to disconnect the closure and distributing member from the lower end of the operating rod. On the other hand, when the pins 12 are not registered with these grooves or slots or the lowest portion of the cam surfaces, the closure and distributing member may be forced upwardly relative to the rod and turned so as to be disconnected therefrom. The device is then open for filling or replenishment, as the case may be. The parts may be suitably marked to indicate the opening position or to indicate the adjustment so that the quantity of distribution may be ascertained.

These articles are made of very few parts and, therefore, can be manufactured quickly and efficiently at a relative minimum expense. The adjustment to provide for a regulated discharge is very simple and the permanent closure of the article may be accomplished by a slight turn of either the operating button 25 on the one hand or the closure or distributing member on the other hand. The operation for distribution is very simple including holding the article between certain fingers and applying pressure to the operating button 30 ton with the thumb or another finger, whereby the customary manipulation or shaking of the article results in an efficient distribution in suitably regulated quantities of the substance contained within the article.

35 This construction lends itself admirably to manufacture from materials which are not subject to corrosion and dampness such as metal, and for this purpose glass, various composition products such as catalin, and the like may be utilized. Using such materials, the article may be made of very ornamental and attractive appearance due to color schemes that may be utilized and the use of contrasting colors for the separate parts.

45 Attention is particularly called to the line contact between the sharp edge 17 and the bevelled surface 3 of the opening into the casing. This construction prevents the retention of any powdered substance between these parts when they contact with each other and also prevents wedging or packing of the material during the closing operation. The entire structure of the closure and distributing member and its connection with the operating rod is designed with the idea of preventing the packing or wedging of the powdered substance during any closing operation. By that is meant that the lines are straight or vertical and there are substantial distances between the stud or projection 50 18 of the closure and distributing member and the inner surfaces of the casing.

What I claim is:—

1. A device of the character described including, in combination, a hollow body por-

tion having its lower end open and having a neck at its upper end, said neck having an opening therethrough, a closure and distributing member adapted to fit the open end of the body portion, a rod connected to said closure and distributing member and slidably extending through said opening in said neck, a button for operating said rod, and cooperating adjustable means between said neck and said button whereby upon proper adjustment of said cooperating means the longitudinal movement of said button and rod may be varied by rotation of said button. 70 75

2. A device of the character described including, in combination, a hollow body portion having its lower end open and having a neck at its upper end, said neck having an opening therethrough, a closure and distributing member adapted to fit the open end of the body portion, a rod connected to said closure and distributing member and slidably extending through said opening in said neck, a button for operating said rod and cooperating means between said neck and said button whereby upon proper adjustment of said cooperating means the longitudinal movement of said button and rod may be varied by rotation of said button, said cooperating means including a cam and projections adapted to engage said cam. 80 85 90 95

3. A device of the character described including, in combination, a hollow body portion having its lower end open and having a neck at its upper end, said neck having an opening therethrough, a closure and distributing member adapted to fit the open end of the body portion, a rod connected to said closure and distributing member and extending through said opening in said neck, a button for operating said rod, and cooperating means between said neck and said button whereby upon proper adjustment of said cooperating means the longitudinal movement of said button and rod may be varied by rotation of said button, said cooperating means including a plurality of stationary cams and a plurality of movable projections adapted to engage said cams. 100 105 110

4. A device of the character described including, in combination, a hollow body portion having its lower end open and having a neck at its upper end, said neck having an opening therethrough, a closure and distributing member adapted to fit the open end of the body portion, a rod connected to said closure and distributing member and slidably extending through said opening in said neck, a button for operating said rod and cooperating means between said neck and said button whereby upon proper adjustment of said cooperating means the longitudinal movement of said button and rod may be varied by rotation of said button, said means including a plurality of cams on said neck and a plurality of adjustable members projecting 115 120 125 130

from said button and adapted to engage said cams.

5. A device of the character described including, in combination, a hollow body portion having its lower end open and having a neck at its upper end, said neck having an opening therethrough, a closure and distributing member adapted to fit the open end of the body portion, a rod connected to said closure and distributing member and slidably extending through said opening in said neck, a button for operating said rod, and cooperating means between said neck and said button and operable by rotary adjustment of the button, whereby upon proper adjustment of said cooperating means the longitudinal movement of said button and rod may be varied by rotation of said button, and a spring member interposed between said button and said neck so as to normally hold the closure and distributing member in closed relation to said body.

25. A device of the character described including, in combination, a hollow body portion having its lower end open and having a neck at its upper end, said neck having an opening therethrough, a closure and distributing member adapted to fit the open end of the body portion, a rod connected to said closure and distributing member and slidably extending through said opening in said neck, a button for operating said rod, a spring interposed between said button and said neck so as to normally hold the closure and distributing member in closed relation to said body and means operable by a rotary movement of the button for limiting the relative downward movement of said button and rod and closure and distributing member.

40. A device of the character described including, in combination, a hollow body portion having its lower end open and having a neck at its upper end, said neck having an opening therethrough, a closure and distributing member adapted to fit the open end of the body portion, a rod connected to said closure and distributing member and slidably extending through said opening in said neck, a button for operating said rod, a spring interposed between said button and said neck so as to normally hold the closure and distributing member in closed relation to said body, and means operable by a rotary adjustment of the button for limiting the relative downward movement of said button, and rod and closure and distributing member, said means being adjustable so as to vary the movement.

55. A device of the character described including, in combination, a hollow casing having an opening at its bottom, a closure and distributing member positioned in said opening, an operating button on top of said casing and having an operative connection with said closure and distributing member where-
60 by when said button is depressed, the closure

and distributing member will be opened, and means operable by a rotary movement of the button for varying the extent of possible downward movement of the button.

65. A device of the character described including, in combination, a hollow casing having an opening at its bottom, a closure and distributing member positioned in said opening, an operating button on top of said casing and having an operative connection with said closure and distributing member whereby when said button is depressed, the closure and distributing member will be opened, and means for varying the extent of longitudinal movement of the button relative to the casing, said means including a plurality of cam surfaces on said casing and a plurality of adjustable projections on said button.

70. A device of the character described including, in combination, a hollow casing having an opening at its bottom, a closure and distributing member positioned in said opening, an operating button on top of said casing and having an operative connection with said closure and distributing member whereby when said button is depressed, the closure and distributing member will be opened, and means operable by a rotary adjustment of the button for varying the extent of longitudinal movement of the button, said closure and distributing member being provided with means for permitting detachment only when the parts are adjusted to permit the greatest relative movement of the operating button.

75. A device of the character described, including in combination, a casing having its lower end open, an operating button on its upper end, an operating rod connected thereto and slidably mounted in the casing, a closure and distributing member connected to said rod and adapted to fit into and close the open end of said casing and means operable by a rotary movement of the button for varying the extent to which said closure and distributing member may be opened.

80. A device of the character described including, in combination, a casing having its lower end open, an operating button on its upper end, an operating rod connected thereto and slidably mounted in the casing, a closure and distributing member connected to said rod and adapted to fit into and close the open end of said casing and means operable by a rotary movement of the button for varying the extent to which said closure and distributing member may be opened, the connection between said closure and distributing member and said rod being provided with means for permitting the detachment of the closure and distributing member only when the adjustment is made for the greatest movement.

85. A device of the character described, including in combination, a casing having its lower end open, an operating button on its

upper end, an operating rod or plunger connected thereto and slidably mounted in the casing, a closure and distributing member connected to said rod and adapted to fit into and close the open end of said casing and means for varying the extent to which said closure and distributing member may be opened, the connection between the closure and distributing member and the rod including a bayonet slot connection and spring means interposed between closure and distributing member and the operating rod so that the closure and distributing member may be partially rotated for detachment only when the adjustment is made to permit opening to the greatest distance.

14. A device of the character described including, in combination, a hollow casing open at one end, a button at the other end, a closure and distributing member for the open end, means connecting said button and said closure and distributing member interposed between the top of said casing and said button to normally hold the closure and distributing member in closed position, said button having a plurality of adjustable projections and said casing having a plurality of cam surfaces acting as abutments to be engaged by said projections when the button is depressed so as to limit the extent of movement thereof, said closure and distributing member being provided with means for permitting detachment from said connecting means only when the parts are adjusted so as to permit the greatest movement of the button.

15. A device of the character described including, in combination, a hollow casing open at one end, an operating member at the other end provided with a closure and distributing member for the open end, said closure and distributing member having its outer edge bevelled or inclined downwardly so as to provide a sharp seating edge to engage the inner surface of the hollow casing, the inner surface of said hollow casing being bevelled oppositely to the bevel of the edge of the closure and distributing member so as to prevent retention of the powdered material therebetween when the parts are in contact.

59 In testimony that I claim the foregoing, I have hereunto set my hand this 6th day of September, 1927.

LESTER B. PLATT.
